(57) **CLAIM**

The ornamental design for an LED light bulb, as shown and described.

DESCRIPTION

FIG. 1 is a top perspective view of an LED light bulb showing my design;

FIG. 2 is a bottom perspective view thereof;

FIG. 3 is a front elevational view thereof, the rear being a mirror image of the front;

FIG. 4 is a right side elevational view thereof, the left side being a mirror image of the right side;

FIG. 5 is a top plan view thereof;

FIG. 6 is a bottom plan view thereof; and,

FIG. 7 is a top perspective view similar to FIG. 1 but showing a variation of our design.

The broken line structure in FIGS. 1, 5 and 7 is for illustrative purposes only, and forms no part of the claimed design.
